UNITED STATES PATENT OFFICE.

FRANK H. CORDUAN, OF BROOKLYN, NEW YORK, ASSIGNOR TO JOHN B. PECK, OF SAME PLACE.

ELECTRIC-LIGHT-WIRE MOLDING.

SPECIFICATION forming part of Letters Patent No. 678,544, dated July 16, 1901.

Application filed December 29, 1899. Renewed June 6, 1901. Serial No. 63,421. (No model.)

To all whom it may concern:

Be it known that I, FRANK H. CORDUAN, a citizen of the United States, and a resident of the borough of Brooklyn, city of New York, 5 in the county of New York and State of New York, have invented certain new and useful Improvements in Electric-Light-Wire Moldings, of which the following is a specification.

This invention relates to improvements in 10 electric-light-wire moldings, such as are used for receiving and holding electric-light wires.

The object of my invention is to provide a 15 new and improved molding of this kind which is simple in construction, effective in use, can be made by machinery in a single and continuous operation, and is inexpensive.

In the accompanying drawings, forming a 20 part of this specification, and in which like letters of reference indicate like parts in all the views, Figure 1 is a transverse sectional view through my improved molding. Fig. 2 is a face view of the under side of the same, the cap-molding being removed. Fig. 3 is a 25 vertical longitudinal sectional view of the molding.

The molding A is provided with two or more longitudinal grooves B in its under side, into 30 which grooves the electric-light wires a are placed and in which they are held by pivoted buttons C, located at suitable intervals, and which, when extending transversely, extend under the wires, and thus hold them in place. As these buttons must not project beyond the 35 face of the molding and must rest snugly on the wires a, it has been customary to rout out a recess in which the button is pivoted, this recess being of uniform depth. This routing necessitates a second operation and requires that the molding be at rest during the routing 40 operation. In my improved molding I gouge

out a recess D in the wood E remaining between the grooves B, and this recess increases in depth from its ends to its center and has a segmental or curved bottom. The button C is pivoted by its pivot F to the center of the 45 curved bottom of said recess, as shown. The ends of the button can give or spring upward sufficiently when turned in line with the length of the molding. By making the recess D in this manner I am enabled to produce 50 them by means of a rotary cutter in the same operation of molding—that is to say, while the wood is being run through the molding-machine to shape it and cut the grooves B the rotary cutter can gouge out the recesses D in 55 parts just previously molded without requiring any rehandling of the wood or a stopping of the molding-machine.

G is a cap-molding.

Having described my invention, what I 60 claim as new, and desire to secure by Letters Patent, is—

An electric-light-wire molding provided with longitudinal grooves for receiving the wires and a recess in the wood between the 65 grooves, which recess has a bottom curved in the direction of the length of the molding, the recess gradually increasing in depth from its ends toward the center and a button pivoted to the bottom of the recess at the center of 70 the same, substantially as herein shown and described.

Signed at New York, in the county of New York and State of New York, this 16th day of October, A. D. 1899.

F. H. CORDUAN.
